UNITED STATES PATENT OFFICE.

JOHN W. HOLADAY, OF AKRON, OHIO.

DESIGN FOR A FURNACE BAR GRATE-SUPPORT.

SPECIFICATION forming part of Design No. 28,852, dated June 14, 1898.

Application filed May 12, 1898. Serial No. 680,518. Term of patent 7 years.

To all whom it may concern:

Be it known that I, JOHN W. HOLADAY, a citizen of the United States, residing at Akron, in the county of Summit and State of Ohio, have invented and produced a new and original Design for Furnace Bar Grate-Supports, of which the following is a full, clear, and exact description, such as will enable others skilled in the art to which it appertains to make and use the same.

My design relates to furnace bar grate-supports.

Figure 1 represents a perspective view of my improved design. Fig. 2 is an end view of the same. Fig. 3 is a cross-section.

The leading feature of my design is a furnace-grate support the top portion of which is provided with a central rib with grate-bar rests upon either side, the opposite end portions having downwardly-projecting ribs.

1 represents my improved grate bar or support. 2 is a vertical web formed on the under side thereof, having transverse ribs at intervals. The top portion of the bar has a

central longitudinal rib 4, with a horizontal 25 surface or grate-rest 5 upon one side thereof, and an angular longitudinal abutment or rest 6 on the opposite side of said central rib 4. The opposite ends of the support or bar 1 have horizontal portions 7 extending across the top 30 thereof and are provided with ribs 8, projecting from side portions 7, so as to provide an air-space under the opposite ends of the bar. The opposite ends of the bar are adapted to rest in or upon the opposite walls of the fur- 35 nace.

Having described my invention, what I claim as new, and desire to secure by Letters Patent, is—

The design for a furnace bar grate-support, 40 substantially as shown and described.

In testimony whereof I affix my signature in the presence of two witnesses.

JOHN W. HOLADAY.
